US0D1044456S

(12) **United States Design Patent** (10) **Patent No.:** **US D1,044,456 S**
Wen (45) **Date of Patent:** **** Oct. 1, 2024**

(54) **COMBINED HINGE HOLE OPENER AND POSITIONER**

(71) Applicant: **Guangzhou Fengsen Machinery Co., Ltd.**, Guangdong (CN)

(72) Inventor: **Tianci Wen**, Hunan (CN)

(73) Assignee: **Guangzhou Fengsen Machinery Co., Ltd.**, Guangdong (CN)

(**) Term: **15 Years**

(21) Appl. No.: **29/905,729**

(22) Filed: **Oct. 25, 2023**

(30) **Foreign Application Priority Data**

Jul. 19, 2023 (CN) 202330453435.1

(57) **CLAIM**

The ornamental design for a combined hinge hole opener and positioner, as shown and described.

DESCRIPTION

FIG. 1 is a front, right and top perspective view of a combined hinge hole opener and positioner, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1; and, FIG. 11 is an enlarged view of detail 11 in FIG. 3.

The broken lines depict portions of the combined hinge hole opener and positioner that form no part of the claimed design. The dot-dash broken lines in FIGS. 1, 3, and 9-11 depict the boundaries of the enlargements that form no part of the claimed design.

1 Claim, 11 Drawing Sheets
